UNITED STATES PATENT OFFICE.

CHARLES J. MARTH, OF ST. LOUIS, MISSOURI, ASSIGNOR TO WAYNE MANUFACTURING COMPANY, OF ST. LOUIS, MISSOURI, A CORPORATION OF MISSOURI.

DRIVING MECHANISM.

1,296,100.

Specification of Letters Patent.

Patented Mar. 4, 1919.

Application filed August 19, 1915. Serial No. 46,400.

To all whom it may concern:

Be it known that I, CHARLES J. MARTH, a citizen of the United States, residing at the city of St. Louis and State of Missouri, 5 have invented a new and useful Driving Mechanism, of which the following is a specification.

This invention relates to improvements in driving mechanisms and more specifically to 10 a driving mechanism which has particular adaptability for driving washing machines and associated coöperating mechanisms for operating upon the work in the various processes of cleansing, wringing, rinsing and re- 15 wringing.

An object of the invention is to provide a driving mechanism actuated from a single source of power which will be simple and durable in construction and adapted in its 20 specific embodiment for operating upon the clothes in the process of cleansing the same and for operating the wringer mechanism associated and coöperating with the washing machine.

25 Another object of the invention is to provide a driving device for imparting vertical reciprocating motion to a vertical shaft and the mechanism controlled thereby at reduced speed from a single drive shaft, associated 30 with mechanism for driving a pair of transverse shafts from an upright shaft, with speed-controlling connections between said drive shaft and said transverse shafts.

Another object of the invention is to provide 35 a driving mechanism carried in a portable support and adapted to be coöordinated with a vertically movable shaft mounted in a support relatively movable to said portable support, in combination with an upright 40 shaft adapted to drive mechanism supported in a swingable frame and carried by said portable support, with provision of gear connections between the mechanisms and the main drive shaft, whereby the mechanisms 45 will be operated at required speeds, either concurrently or separately and independently as desired.

The invention consists in the construction, arrangement and combination of the 50 various parts, whereby the objects mentioned and additional advantages and features may be attained as hereinafter more fully disclosed, reference being made to the accompanying drawings, in which:—

55 Figure 1 is a front elevation of a washing

machine and associated wringer mechanism with supports therefor, showing the improved driving mechanism of the present invention embodied therein;

Fig. 2 is a rear elevation of a washing 60 machine and associated wringer mechanism and support therefor, further illustrating the embodiment of my invention;

Fig. 3 is a top plan view of the same construction; 65

Fig. 4 is a bottom plan view of the same mechanisms;

Fig. 5 is a side elevation of the washing machine and associated wringer mechanism, with a portion of the tub of the washing 70 machine broken away to more fully illustrate the embodiment of the mechanism of the present invention, and

Fig. 6 is a detailed view, showing a portion of the mechanism for setting one of the 75 controlling levers.

In the embodiment of the invention illustrated in the drawings, a portable support for the driving mechanism is provided. As illustrated the support comprises a rectangular frame composed of end members 1 and side members 2, which are supported at an elevation by legs or standards 3. The legs or standards are reinforced, preferably, by obliquely disposed reinforcing strips 4 secured to the end members 1 at one end and to the legs or standards at the other end, in the manner clearly illustrated in Figs. 1 and 2 of the drawings. Longitudinal reinforcing strips 5 extending from leg to leg 80 on one side assist in imparting rigidity to the support. 85

In practically constructing the portable support it has been found eminently suitable to construct the same from angle-iron which 90 provides a frame that is durable in use, inexpensive in construction and readily portable.

In order to provide a platform for supporting a tub or other container, transverse 100 slats 6 are mounted in the frame member and are preferably bolted or otherwise secured to the side members 2 in the manner clearly illustrated in Figs. 3 and 4 of the drawings. The slats 6 are mounted in substantially one-half of the frame so that the remaining section thereof is open and free to receive a removable support comprising, in the embodiment shown, a tub 7 of a washing machine. The tub 7 has secured to the 110

sides thereof a series of suitably arranged brackets 8 which are adapted to rest upon the upper face of the lower leg of the side members 2 and one of the end members 1, 5 so that the tub may be bodily lifted in or out of the frame.

The upright support 9, in the form of a tubular casing, is secured to the inner one of the slats 6 and is adapted to support a 10 swingable bracket for the wringer frame. The bracket comprises a sleeve 10 which rests upon and is supported by the member 9 and has extending transversely thereof a cross-member 11 provided at its outer extremity with a hand-hold 12 and a bracket 15 13 extending from the upper portion of the sleeve and constituting a journal for the drive shaft of the wringer.

The wringer proper is of the usual construction and comprises a frame 14 which is mounted upon the cross-member 11. Wringer-rolls 15 of usual design and tensioned by the usual tension mechanism are mounted in the frame 14, it being, of course, 20 understood that one of the wringer rolls is mounted upon a shaft 16 which extends beyond the wringer frame and is journaled in the bracket 13.

An upright shaft 17 extends through the 25 members 9 and 10 and is provided at its upper end with a beveled gear 18 which meshes with a gear 19 secured to the drive shaft 16 of the wringer mechanism. The wringer support is swingable about the shaft 30 35 17 and is adapted to be locked in different angular adjustments by means of a latch-bolt 20 adapted to engage within a series of keepers 21, 22 and 23, the keeper 21 being secured to the side of the tub and the keepers 22 and 23 being in the form shown as tubular upright members secured in suitable 40 45 adjustments to the frame.

The supplemental support, comprising end members 24, legs 25 and supporting-braces 26, is arranged adjacently to the main support and is provided with transverse slats 27, constituting a platform for supporting a tub or other receptacle. It will be noted that the keeper devices 22 and 23 are 50 55 so arranged that the wringer may be locked at angles of ninety degrees so that after the clothes have been withdrawn from the tub of the washing machine, they may be wrung out and delivered into a separate tub or container supported upon the forward part of the main portable support, the wringer adjusted to a position transverse of its original position and the clothes transferred from the first receptacle to a receptacle placed upon the adjacent end of the supplemental support, after which the wringer may be positioned and locked in the member 23 and the clothes advanced to a container supported on the other end of 60 65 said supplemental support.

The washing machine mechanism as I have illustrated it includes the tub 7, which is provided with a hinged cover 28. A tubular standard 29 is supported within the tub in an upright position substantially in the center thereof, said standard being bolted or otherwise secured to the bottom of the tub, in the manner clearly illustrated in Fig. 5 of the drawings. An agitator-shaft 30 is slidably mounted within the standard 29 and is of a length sufficient so that it extends above the upper end thereof and below the lower end of the standard through an opening in the bottom wall of the tub. 70 75

The mechanism for operating upon the clothes contained in the tub may be of any suitable design or construction. As I have shown it, it includes a hub-member 31 in the form of a hollow cylinder from the lower end of which extends obliquely-inclined legs 32 which support at their lower ends an annular plate 33. The interior diameter of the hub-member 31 is such that when in position it will fit over the upper end of the standard 29, so that when the shaft 30 is reciprocated the agitator-element will be held in proper adjustment and guided in its reciprocating movement so that it may move in an up and down path, true to its axis. 80 85 90

A hood or pounder 34, which is conical in form, is bolted to the plate 33, there being a horizontally adjusted plate 35 extending over the apex of the hood or pounder, the parts being connected as clearly shown in Fig. 5 of the drawings. 100

It will be noted that this construction provides a guide-way or support in which the agitator-shaft is slidable, and that the shaft will be held in true alinement as it is reciprocated up and down by the hub-member fitting over the upper end of the support. While I have described a particular form of mechanism for operating upon the clothes, it will of course be understood that the design of the construction may be changed and that the present invention contemplates only the provision of a suitable support rigidly mounted upon the removable support, in the form of a tub, in which the reciprocating shaft for actuating the mechanism for operating upon the clothes is mounted. 105 110 115

The driving mechanism for actuating the mechanism for operating upon the work supported by the tub and actuating the associated and co-operating wringer-mechanism, 120 comprises a driven-shaft 36 journaled in hangers 37 and 38 which depend and are secured to a portion of the portable frame work or support, and as illustrated are secured to the under face of the inner ones of the cross-members 6. The shaft 36 carries upon its outer end, which extends beyond one side of the frame member, a belt-wheel or pulley 39 and at its inner end a gear-wheel 40. Supported above the shaft 36 and ex- 125 130

tending parallel therewith is a counter-power shaft 41 journaled to rotate in bearings 42, 43 and 44 also supported by the inner one of the cross-members 6 of the main portable-support. The counter-drive shaft 41 is provided with a gear-wheel 45 adapted to mesh with and be driven by the gear-wheel 40. The ratio of the gears 40 and 45 is such that the speed of rotation of the shaft 41 will be reduced with respect to the rate of rotation of the shaft 36. The gear-wheels 40 and 45 thereby constitute a speed-reducing connection between the shaft 36 and the shaft 41.

The shaft 41 extends from side to side of the portable-support and carries at one end a sprocket-wheel 46 which is loose upon the shaft 41, and is provided with a hub-member 47 designed to constitute one member of a clutch for locking and releasing the sprocket-wheel 46 to and from the shaft 41. A co-operating clutch-element 48 is feathered on the shaft 41 and is adapted to be moved into and out of contact with the clutch-member 47 by a lever 49.

The lever 49 is pivoted at 50 to an arm 51 of a bracket 52 supported at one side of the portable-support. The pivot 50 is in the form of a bolt which passes through the arm 51 and has an expansion spring 53 encircling it and bearing against the rear face of the lever 49, the tendency of which is to press the lever forwardly against the arm 51. The lever 49 extends through a slot 54 in the inner one of the slats 6. A bracket 55 extends inwardly from one of the side members 2 and has a lug or projection 56 which extends toward the slot 53. The lever 49 is also provided with a lug or projection 57, the lugs 56 and 57 constituting a lock-device, so that when the lever 49 is swung to either one side or the other of the lug 56 the lever will be pressed inwardly by the spring 53, the lug or projection 57 retaining the lever 49 from accidental lateral movement.

Mounted in a bracket 58, bolted to the lower face of the bottom wall of the tub 7, is a shaft 59, one end of which extends beyond the side wall of the tub and has secured near its outer end a sprocket 60. A sprocket-chain 61 operatively connects the sprocket-wheel 46 with the sprocket 60, the sprockets 46 and 60 together with the chain 61 constituting a drive-connection between the shaft 41 and the shaft 59. The inner end of the shaft 59 is provided with a gear-wheel 62 and is adapted to mesh with a gear-wheel 63 carried by a shaft 64 which is journaled in the bracket 58 above the shaft 59.

The ratio of the sprockets 46 and 60 is such that the shaft 59 will be driven at a reduced speed with respect to the shaft 41, and a reduction of the speed of the shaft 64 with respect to the shaft 59 may be attained by suitably arranging the ratio of the gears 62 and 63.

The inner end of the shaft 64 is provided with a crank-arm 65, the free end of which is adapted to engage in an oblong-slot 66, formed in the plate 67. The plate 67 carries in its rear face a boss 68 which is provided with an opening through which the agitator-shaft 30 extends. A set screw 69 is threaded into the boss 68 and provides means for detachably and adjustably connecting the plate 67 with the agitator-shaft. In order to support the free end of the agitator-shaft the bracket 58 is equipped with a yoke 70, at the extremities of the arms of which are formed openings through which the shaft 30 extends. From this construction it results that the end of the shaft 30 is held in proper adjustment, as vertical reciprocating movement is imparted thereto from the shaft 64 by means of the crank-arm 65 operating in the slot 66.

The lower end of the shaft 17 which extends below the portable-support has affixed thereto a beveled-gear 71 which is adapted to mesh with a pair of bevel-pinions 72 and 73 which are loosely journaled on the shaft 41. The pinions 72 and 73 are spaced apart and arranged on either side of the axis of the shaft 17 and are equipped with clutch-members 74 and 75 which are adapted to co-operate with a double-faced clutch-sleeve 76 which is feathered on the shaft 41. An arm 77 is connected to the sleeve 76 and is adapted to be operated by a push-rod and lever construction 78 and 79. The lever 79 is pivoted to an arm 80 formed integral with the bracket 52.

The space between the inner faces of the clutch-members 74 and 75 is sufficient so that the clutch sleeve 76 may be engaged with either one or the other of said clutch-members, or may be set in neutral position between them. It will be obvious that by locking the shaft 41 with either one or the other of the bevel-pinions 72 or 73 the shaft 17 will be rotated in either direction and thereby the wringer mechanism may be driven in reverse directions.

From the foregoing description of the construction and operation of the mechanism it will be understood that I have provided a driving mechanism adapted to operate a vertically reciprocating washing mechanism, in combination with means for driving the wringer mechanism in reverse directions from a common source of power, and that the driving mechanism is so controlled that the washing mechanism and the wringer mechanism may be operated conjointly or independently, as desired. It will also be observed that provision is made for driving the wringing mechanism in different angular positions.

It will be understood that numerous changes may be made from the specific embodiment illustrated and described and I do not wish to limit myself, therefore, to the

exact details of construction, but what I claim and desire to secure by Letters Patent is:—

1. Mechanism of the character described, comprising a portable support, a work support mounted on said portable support, a guide supported by said work support, an axially movable shaft mounted vertically in said guide, a horizontal drive shaft supported by said portable support, a driven shaft disposed horizontally in said portable support, mechanism for driving said driven shaft at reduced speed from said drive shaft, and mechanism operated by said driven shaft for imparting a vertical reciprocatory motion to said vertical shaft when said work support is in position on said portable support.

2. Mechanism of the character described, comprising a portable support, a horizontal drive shaft carried by said support, a work support mounted on said portable support, a bottom wall in said work support, a vertical shaft carried by and extending above and below the bottom wall of said work support, mechanism supported by said vertical shaft above said bottom wall for operating upon the work, and connections driven by said drive shaft for imparting a vertical reciprocatory motion to said vertical shaft by the continuous rotation of said drive shaft.

3. Mechanism of the character described, comprising a portable support, a horizontal drive shaft supported below said support, a second horizontal shaft supported below said support, connections for driving said second shaft at reduced speed from said drive shaft, a second work support mounted on said portable support, a vertical shaft carried by said work support and extending below said second shaft, connections between said second shaft and said vertical shaft, whereby said vertical shaft will be operated axially by the continuous rotation of said second shaft in one direction, and mechanism supported by said vertical shaft and movable in directions toward and away from the work.

4. Mechanism of the character described, comprising a support, a horizontal drive shaft carried by said support, means for revolving said drive shaft continuously in one direction, a second horizontal shaft, a connection between said drive shaft and said second shaft for revolving said second shaft at reduced speed in the same direction with said drive shaft, a vertically movable mechanism for operating upon the work above said support, and connections operated by said second shaft for moving said mechanism in directions toward and away from the work carried by said support by the continuous rotation of said drive shaft and said second shaft in one direction.

5. Mechanism of the character described,

comprising a portable support, a work support carried by said portable support, operating mechanism mounted in said work support adapted to reciprocate in a vertical path above the work supported on said work support, a horizontal drive shaft mounted in said portable support, a second horizontal shaft carried by said portable support, driving connections between said two horizontal shafts whereby the latter is driven at a reduced speed in respect to the former, and connections between said second-named horizontal shaft and the mechanism carried by said work support for reciprocating said mechanism when said work support is in position on said portable support.

6. Mechanism of the character described, comprising a portable support, a work support removably mounted on said portable support, an axially movable vertical shaft carried by said work support, a guide supported by said removable support in which said shaft is vertically slidable, a drive shaft supported by said portable support, a driven shaft carried by said portable support, gear connections between said drive shaft and said driven shaft whereby said driven shaft is driven at a reduced speed with respect to said drive shaft, a second shaft mounted in said work support, driven mechanism for driving said second-named driven shaft at a reduced speed from said first-named driven shaft, and mechanism operated by said second-named driven shaft for reciprocating said vertical shaft axially when said removable support is in position on said portable support.

7. In driving mechanism, the combination with a support, a drive shaft carried by said support, means for driving said drive shaft, a driven shaft carried by said support, operating connections between said drive shaft and said driven shaft, whereby said driven shaft is driven continuously in one direction at a reduced speed from said drive shaft, a second driven shaft mounted in a separate support from said first-named support, connections for driving said second driven shaft at a reduced speed with respect to said first-named driven shaft, a third shaft entrained with said second-named driven shaft, a crank arm connected with said last-named shaft, an upright shaft, and connections between said upright shaft and said crank arm whereby said upright shaft is reciprocated.

8. In driving mechanism, the combination with a support, a drive shaft mounted in said support, a driven shaft mounted in said support parallel with said drive shaft, speed reducing driving mechanism between said drive shaft and said driven shaft, a second support removably mounted on said first-named support, a driven shaft in said second-named support, speed reducing driving connections between the driven shaft in said

first-named support and the last-named shaft in said second-named support, a second driven shaft in said second-named support, gear connections between the first mentioned shaft in said second-named support and the second-named shaft in said second-named support for driving said second-named shaft at a reduced speed with respect to said first-named shaft, an upright shaft in said second-named support, and means for changing 10 the rotary motion of said second-named

shaft in said second-named support to vertically reciprocating motion in said upright shaft.

In witness whereof I have signed this 15 specification in the presence of two subscribing witnesses.

CHARLES J. MARTH.
